UNITED STATES PATENT OFFICE

99,111

DESIGN FOR A WINDOW BRUSH

Frederic J. Bickel, Cleveland, Ohio, assignor to
The Osborn Manufacturing Company, Cleve-
land, Ohio, a corporation of Ohio

Application February 11, 1936, Serial No. 61,095

Term of patent 14 years

To all whom it may concern:

Be it known that I, Frederic J. Bickel, a citizen of the United States and a resident of Cleveland, county of Cuyahoga, and State of Ohio, have invented a new, original, and ornamental Design for a Window Brush, of which the following is a specification, reference being had to the accompanying drawing, forming a part thereof.

Fig. 1 is a perspective view of a window brush showing my new design;

Fig. 2 is a side elevation;

Fig. 3 is a top view;

Figs. 4 and 5 are transverse sections of the back (omitting bristles), on the planes 4—4, and 5—5, respectively, Fig. 3.

The brush shown is characterized by a back having a top slightly convex transversely, and decidedly convex longitudinally, but with a central flat plateau of approximately elliptical outline.

The sides and ends are vertical, with ends convex as seen in plan. The edges of various surfaces, except the plateau, are joined on short radius curves.

What I claim is:

The ornamental design for a window brush substantially as shown and described.

FREDERIC J. BICKEL.
